UNITED STATES PATENT OFFICE.

JAMES T. CONNELLY, OF HUNTINGTON, WEST VIRGINIA.

DEVICE FOR TAPPING STAY-BOLT HOLES.

SPECIFICATION forming part of Letters Patent No. 373,815, dated November 29, 1887.

Application filed August 18, 1887. Serial No. 247,280. (No model.)

To all whom it may concern:

Be it known that I, JAMES T. CONNELLY, a citizen of the United States, residing at Huntington, in the county of Cabell and State of

5 West Virginia, have invented certain new and useful Improvements in Screw-Taps and Devices for Cutting Threads of Stay-Bolt Holes in Fire-Boxes, Boilers, &c.; and I do hereby declare the following to be a full, clear, and 10 exact description of the invention, such as will enable others skilled in the art to which it appertains to make and use the same.

My invention relates to screw-taps for threading stay-bolt holes of locomotive fire-boxes, boilers, &c., where such stay-bolt holes are behind the frame of the boiler or locomotive, without removing the frame or otherwise disturbing the engine.

Fire-boxes of locomotives are generally 20 made of an inner and an outer metal sheet or sheets, with a water-space between them, and are held in place and securely braced by numerous stay-bolts. The inside and outside shells of the fire-box are subjected to great 25 strain and wear, and the stay-bolts are, consequently, frequently broken or become worn out and have to be replaced. Some of these stay-bolts are placed in the fire-box behind the frame or other portion of the boiler, and, heretofore, to replace one of these worn-out or 30 broken bolts, it was necessary to remove the intervening frame from the outside of the engine before a new bolt could be fitted in place. The removal of the frame must be executed by skilled workmen, and is a tedious and expensive operation and requires much time; and it is a well-known fact to those skilled in the art to which my invention appertains that when the frame or other part of the boiler or 35 locomotive has been removed to replace a worn-out stay-bolt which is located behind said frame, and then replaced again, the replaced frame or part is never as strong as it was before being removed.

40 The object of my invention is to replace old stay-bolts with new ones without removing the frame or otherwise disturbing any of the parts of the engine behind which said bolts are placed, and this end I accomplish by first removing the old bolt and then rethreading the stay-bolt hole from the inside of the fire-box, and by then inserting a new stay-bolt from the

inside of said box, which may thus be done quickly and effectively at comparatively little expense and without injury to the frame-work 55 of the boiler.

The subject-matter claimed herein by me as of my invention is first described below, and is then particularly pointed out at the close of this specification.

60 The accompanying drawings illustrate my improved apparatus, and in said drawings Figure 1 is a view in elevation of the tubular screw-tap used for threading the stay-bolt holes; and Fig. 2 is an end view thereof, looking at the rear, squared, or wrench end of the tap. Fig. 3 is a view of a spindle or rod having an enlargement or shoulder at one end for use with the tubular screw-tap. Fig. 4 is a view of another spindle or rod for use with 65 said tap in replacing stay-bolts according to my improved method; and Fig. 5 is a sectional view of a portion of a locomotive fire-box, showing the inner and outer shells of the fire-box and illustrating my improved tools in different stages of operation while threading stay-bolt holes, and also showing the relation the 70 several parts of the device bear to each other.

In carrying out my invention, I make use of a tubular screw-tap, A, the longitudinal bore 80 a of which extends entirely through it, and this tubular tap is fitted to work upon a spindle or rod, B, with an annular enlargement or shoulder, b, at one end, and upon a similar straight rod or spindle, C, minus the enlargement or head of the rod B, in another step of the operation of threading the bolt-holes in the inner and outer shells of the fire-box. The tubular tap A is squared at one end, as at A', for the application of a wrench, as usual. The 85 fire-box is shown as consisting of the usual inner and outer shells, D and D', united at bottom by the usual bar, F, and it will be seen that some of the stay-bolts G thereof are placed behind the boiler frame-work, (shown at E E';) 90 and to replace a worn-out stay-bolt which is placed behind said frame the frame E has heretofore been removed.

To avoid removing the frame-work E of the engine or boiler when it is desired to replace 95 an old stay-bolt, and attain the consequent saving of time, labor, expense, and injury to the engine, is the main object of my invention, which may be practiced as follows: The work-

man, from the inside of the fire-box, first extracts the old bolt from the hole into which it was first fitted and leaves the stay-bolt hole clear, as at d and d' , Fig. 5. The spindle B is now passed from the inside of the fire-box through the hole d' in the inside sheet or shell, D', until the enlarged annular end b of the spindle B rests in the hole d of the outside sheet or shell, D, and against the frame-work E, which is opposite the hole d , as shown in Fig. 5. The tubular screw-tap A is now fitted on the spindle B, said spindle B passing through the longitudinal bore a of said tap, and the tap A is turned by means of a wrench, as usual, placed on the squared end A', and cuts the thread in the walls of the hole d' of the inside sheet or shell, D'. It will thus be seen that as the enlarged end b of the spindle B fits in the hole d of the outside sheet or shell, D, and the screw-tap A fits in the hole d' of the inside sheet or shell, D', the tap A is positively directed and guided in a right or straight line relatively to the holes d and d' as it threads the walls of said hole d' , and is compelled to cut the thread of said hole in a right line with the hole d in the outer shell, D. When the hole in the inner shell, D', is threaded, the spindle B, together with the tap A, is removed from the holes d and d' , and the spindle C is inserted instead thereof, with the tap A fitted thereon as with the rod B, as shown also in Fig. 5. As the spindle C has no enlargement on its outer end, which is placed in the hole d of the outer shell, D, the screw-tap A is allowed to cut its thread in the walls of said hole

d while also turning in the hole d' of the inner shell, D'; and, with one end working in the hole d and the other passing through the hole d' and guided by the rod C, the tap A is necessarily guided in a straight line and is forced to cut a thread in the hole d of the outer shell, D, exactly corresponding as to pitch and coincidence to the thread of the opposite stay-bolt hole, d' , in the inner shell, D'. The stay-bolt holes of both the inner and the outer shells of the fire-box having thus been threaded without removing the frame-work E of the boiler or engine, or otherwise disturbing the engine, and exactly corresponding one with the other, constitute a perfectly-threaded hole for the reception of the new stay-bolt, which can be inserted, in the ordinary manner, from the inside of the fire-box.

I claim as my invention—

1. The tubular screw-tap, substantially as described.

2. The combination of the tubular screw-tap having its bore extending its entire length with a guide-rod upon which it works, substantially as described.

3. The combination of the screw-tap having a longitudinal bore therein with the guide-rod or spindle having an enlargement at one end thereof, substantially as described.

In testimony whereof I affix my signature in presence of two witnesses.

JAMES T. CONNELLY.
